UNITED STATES PATENT OFFICE.

FRED V. HART, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF MAKING HEELS.

1,361,053.

Specification of Letters Patent.

Patented Dec. 7, 1920.

Application filed October 26, 1917. Serial No. 198,609.

To all whom it may concern:

Be it known that I, FRED V. HART, a citizen of the United States, residing at Lynn, in the county of Essex and State of Massachusetts, have invented certain new and useful Improvements in Methods of Making Heels; and I do hereby declare the following to be a full, clear, and exact description of the invention, such as will enable others skilled in the art to which it appertains to make and use the same.

This invention relates to a method of making heels and more particularly to an improved method of preparing lifts for use in building wedge heels. The method is peculiarly adaptable to cutting lifts from prepared sheet heel-stock of which many different kinds are available, known under different trade names. For simplicity of nomenclature the heel-stock material will be referred to hereinafter by the term "leatherboard," used in an inclusive sense.

The object of the present method is to so prepare the individual lifts from the sheet-stock as to eliminate any waste of material, and to enable heels to be built more accurately.

The mode of carrying out the improved method to the best advantage will be apparent from the following description of the steps to be followed, and from the appended claims, by which the essential features are pointed out.

An understanding of the improved method will be assisted by reference to the accompanying drawings in which:

Figure 1 is a side view of a heel block built from lifts prepared by the new method of cutting from sheet-stock, such lifts including two of wedge form; Fig. 2 is a breast end view of the heel block shown in Fig. 1; Fig. 3 illustrates the kind of cut to be made in reducing a sheet of leatherboard to strips, which are later to be cut into even lifts of polygonal outline; Fig. 4 illustrates the kind of cut to be made in severing from the strips the even lifts which are to be used above the wedge lifts, as shown in Fig. 1; Fig. 5 illustrates the kind of cut to be made in severing from the sheet the even strips which are to be used in obtaining, by cuts like those in Fig. 4, the even lifts to be used below the wedge lifts, as shown in Fig. 1; Fig. 6 illustrates the kind of cut to be made

in reducing a sheet of leatherboard into strips from which wedge lifts of polygonal outline are to be formed; Fig. 7 illustrates the step of cutting the leatherboard strips into two wedge strips; and Fig. 8 illustrates the kind of cut to be made in severing the wedge strips into wedge lifts.

For ease of explanation, the following description will be confined to the production of tetragonal lifts. Referring now to the accompanying drawings illustrating the preferred steps to be employed in carrying out the method it should first be pointed out that in Figs. 1 and 2 the dotted lines are intended to show the saving of stock, in favor of the improved method of cutting lifts, over that at present commercially used. In cutting lifts by dies, which is the present universal practice, the plane of the edge is normal to the planes of the faces. Consequently when such lifts are piled in heel form, for a pitched heel the sides and back are stepped as indicated by the dotted lines in Figs. 1 and 2. This is true also of the wedge lifts in a wedge heel; and furthermore all even lifts on the heel seat side of the wedge lifts will project beyond the finished heel line at the breast, as well as at the sides and back, as indicated by dotted lines in Fig. 1. All of this material projecting beyond the finished heel line is wasted by trimming. It also is difficult to register lifts cut by dies accurately. In consequence of an inaccurate registry more material must be removed in the heel shaving operation than is necessary, resulting in the production of a smaller heel than would otherwise be obtained, from the same amount of material, were the registry accurate.

It is obvious that if lifts can be cut in such manner as to cause the contacting faces of adjoining lifts in the heel pile to coincide in outline the full value, or greatest possible size of heel, may be obtained from the piled lifts; and at the same time, since the entire heel surface will be smooth, less material need be removed in the heel shaving operation. As a corollary, more lifts can be obtained from any given area of sheet heel-stock. To these ends it is proposed to prepare the lifts in such manner that their edges will form a smooth lateral surface when assembled in a heel pile. The simplest solution of the problem is to sever the lifts

in the manner hereinafter described; although their edges might be prepared in the desired manner by different modes of treatment, as will occur to those skilled in the art.

Referring first to Figs. 3 to 5 illustrating the preparation of even lifts for a pitched heel, the sheet of leatherboard 10 is first cut into strips 12 by a knife 14 having a cutting edge which will produce a strip edge 16 at one side of the cut, the plane of which is normal to the faces of the sheet, and a strip edge 18 at the other side of the cut, the plane of which is oblique to the faces of the sheet. Each strip 12 is then divided into rectangular even lifts 20 by a second knife 22 the cutting edge of which is so formed as to produce two oblique edges 24 at the opposite sides of each lift. Having produced lifts of different sizes in this manner, in building an unwedged, pitched heel the edges 16, 18 and 24 will be used for the breast, back, and sides of the heel, respectively. Care having been taken to insure that the obliquity of the edges 18 and 24 shall equal the pitch of the back and sides of the heel it is desired to build, it will be apparent that adjoining lifts in the heel pile will coincide in outline and they can, therefore, be registered accurately.

Such lifts as just described will build properly into a wedge heel when placed above the wedge lifts, as shown in Fig. 1, but they will not build properly below the wedge lifts because their right-angled breast edges will project beyond the plane of the heel breast. For producing the even lifts below or at the heel seat side of the wedge lifts, a sheet 11 is severed in strips by a knife 26 (Fig. 5) which enters the face of the sheet at an angle and has a cutting edge which produces two oblique edges 28 and 30 on the strips 13. The angle of the cut is such that the strip edge 30 is of less obliquity, with reference to the faces of the strips, than the strip edges 18, and the strip edge 28 is of sufficient obliquity to form a flat heel breast when rectangular even lifts 32 (Figs. 1 and 2) are cut therefrom, by the step illustrated in Fig. 4, and assembled with the other even lifts 20 and the intermediate wedge lifts 34. It will be noted that a cross-section of the lifts 32, from breast to back, is in the form, substantially, of a rhomboid.

In producing the wedge lifts 34, for use in a wedge heel, a sheet of leatherboard 15 is severed into strips 36 by a knife 26 (Fig. 6) having a cutting stroke in a plane at an angle to the face of the sheet, as in cutting the strips for the even lifts 32 (see Fig. 5) but in this step care should be taken to produce, as nearly as possible, strip edges 38 having an obliquity to the faces of the sheet equal to the obliquity of the strip edges 18. A splitting knife 40 is then used to split the strips 36 in two wedge strips 42, as indicated

by the dotted lines in Fig. 7. In the final step of producing wedge lifts a knife 22 divides each wedge strip 42 into tetragonal wedge lifts 34 having oblique side edges, as in cutting the even lifts 20 (see Fig. 4). It will be noted that a cross-section of the lifts 34, from breast to back, is in the form, substantially, of an oblique triangle.

It will be understood that a quantity of lifts of varying areas are produced from the sheets by the operations just described and these are given to the heel builder who thereafter, by known methods, assembles them in a graded pile as shown in Fig. 1, in such order as may be desired for any given style of heel, placing the even lifts 32 always at the heel seat side of the wedge lifts 34 and the even lifts 20 at the tread face side of said wedge lifts. When this is done a rough heel, or heel block, results, in which the lifts are in perfect registry and which has a vertical breast 44, a smooth pitched back 46 (Fig. 1), and smooth oblique sides 48 (Fig. 2). This heel block may then be shaved to heel form in a machine of the type illustrated and described in Letters Patent of the United States to Erastus E. Winkley No. 1,102,310, dated July 7, 1914, it being obvious that only the minimum amount of material need be removed since the lateral surface of the heel is already of the desired pitch, or slope, with reference to the tread face.

The nature and scope of the invention having been indicated and the preferred mode of practising the method having been described, what is claimed as new, is:—

1. The method of making heels which includes the steps of preparing a plurality of individual lifts of varying area, each with lateral surfaces of the same obliquity as the desired pitch of the corresponding surface of the heel; and then registering said lifts on each other in a graded pile.

2. The method of making heels which includes the steps of producing a series of individual lifts of varying area, each of which has a different area at each face but all of which have the area of one face equal to the area of one face of another lift of the series; and then assembling the lifts with their faces of equal area adjoining.

3. The method of making heels which includes the steps of producing a series of lifts comprising a plurality of even lifts and at least one wedge lift, all of varying area, all of said lifts having oblique edges at the back and sides and some of said even lifts having vertical edges at the breast ends; and then registering said lifts on each other in a graded pile with said even lifts having vertical edges all at the tread face side of the wedge lift or lifts.

4. The method of making heels which includes the steps of producing a series of lifts comprising a plurality of even lifts

and at least one wedge lift, all of varying area; all of said lifts having oblique edges at the back and sides but some of said even lifts having vertical breast edges and one 5 or more having oblique breast edges; and then registering said lifts in a graded pile with said even lifts having vertical and oblique breast edges at the tread face side and at the heel seat side, respectively, of 10 said wedge lift or lifts.

5. The method of making heels which includes the steps of producing a series of lifts comprising a plurality of even lifts and at least one wedge lift, all of varying 15 area, and all having lateral surfaces of such obliquity to the lift faces as to provide a smooth, pitched lateral heel surface and a vertical heel breast when registered in a graded pile; and the registering said lifts 20 in a graded pile.

6. The method of making heels which includes the steps of preparing a plurality of individual polygonal lifts of varying area each with lateral surfaces of the same 25 obliquity as the desired pitch of the corresponding surface of the heel; registering said lifts on each other in a graded pile; and shaving the lateral surface of said pile to heel form.

30 7. The method of making wedge lifts from sheet heel-stock which comprises dividing the sheet in strips by a series of spaced cuts in parallel planes at an oblique angle to the surface of the sheet; severing 35 each strip in two parts by a diagonal cut

across its end which intersects each side edge substantially at a corner; and dividing each wedge strip thus obtained into wedge lifts by severing it widthwise at intervals.

8. The method of making wedge lifts from 40 sheet heel-stock which comprises dividing the sheet in strips by a series of spaced cuts in parallel planes at an oblique angle to the surface of the sheet; severing each strip in two parts by a diagonal cut across its end 45 which intersects each side edge substantially at a corner; and dividing each wedge strip thus obtained into wedge lifts by severing it widthwise, at intervals, by a cutting stroke in a plane normal to the surface of the 50 strip.

9. The method of making wedge strips for use in the production of wedge lifts which comprises dividing sheet heel-stock 55 in strips by a series of cuts in parallel planes at an oblique angle to the surface of the sheet; and splitting each of said strips in a plane extending through the side edges from substantially the lower corner at one edge to substantially the upper corner at the other 60 edge.

10. The method of making wedge heels from differently proportioned wedge and even lifts which includes preparing the rear and side edges of each lift individually in 65 such manner that when assembled together to form a tapering heel pile the oblique surfaces thereof will be smooth, and assembling said lifts.

FRED V. HART.

Corrections in Letters Patent No. 1,361,053.

It is hereby certified that in Letters Patent No. 1,361,053, granted December 7, 1920, upon the application of Fred V. Hart, of Lynn, Massachusetts, for an improvement in "Methods of Making Heels," errors appear in the printed specification requiring correction as follows: Page 2, line 75, for the word "carying" read *varying*; page 3, line 19, for the article "the" read *then*; and that the said Letters Patent should be read with these corrections therein that the same may conform to the record of the case in the Patent Office.

Signed and sealed this 4th day of January, A. D., 1921.
